UNITED STATES PATENT OFFICE.

WILLIAM H. DOUGLAS, OF BELLEVILLE, NEW JERSEY, ASSIGNOR TO HEALEY & COMPANY, OF NEW YORK, N. Y., A CORPORATION OF NEW YORK.

CLAMP FOR WIND-SHIELDS.

1,247,242.

Specification of Letters Patent. Patented Nov. 20, 1917.

Application filed February 9, 1915. Serial No. 7,188.

To all whom it may concern:

Be it known that I, WILLIAM H. DOUGLAS, a citizen of the United States, and resident of Belleville, in the county of Essex and 5 State of New Jersey, have invented a new and useful Improvement in Clamps for Wind-Shields, of which the following is a specification.

This invention relates to an improvement 10 in clamps for wind-shields, with the object in view of providing a clamp which will be effective, cheap in construction and easy to manufacture.

Another object is to provide a device 15 whereby the wind-shield may be removed and replaced very readily without disturbing the clamp or stationary portion of the supporting structure.

A practical embodiment of my invention 20 is represented in the accompanying drawings, in which—

Figure 1 represents in detail portions of 25 the wind-shield and roof of an automobile with the device as applied to one side thereof,

Fig. 2 represents a transverse section of 30 the same taken in the plane of the line A—A of Fig. 1,

Fig. 3 represents a detail central longitudinal section on an enlarged scale, taken 35 through the clamp and a portion of the wind-shield frame,

Fig. 4 represents a central section taken at 40 right angles to Fig. 3, and

Fig. 5 represents a horizontal section 45 taken in the plane of the line B—B of Fig. 3.

The clamp consists of a stationary member and a swinging member. The stationary member comprises a post 3, which may 50 be secured between the usual support, not shown, and the roof 4, for supporting one side of the wind-shield. This post is shown as provided with a head 6 formed integral therewith and having a cylindrical socket 45 7 therethrough forming an exteriorly unbroken wall.

A slot 8 leads from the socket 7 to a point 55 9, thereby forming walls 10, 11, which are adapted to be drawn toward each other by means of a thumb screw 12, passing freely through the wall 10 and having a screw-threaded engagement with the wall 11. The walls of the slot and socket form an unbroken continuation of the post.

A friction washer 13 may be placed be-

tween the wall 10 and the head of the thumb screw 12.

The swinging member comprises a hub 14 adapted to rotate in the socket 7, which hub is held therein by a plate 15 which overlaps 60 the outer face of the head 6 and is secured to the hub by means of a screw bolt 16. The swinging member is further provided with a channel 17 cut therethrough for the reception of the frame 18 of the wind-shield glass 65 19. The frame 18 is secured in the channel 17 by means of ears 20 carried by the frame and screws 21 having a threaded engagement with the swinging member. By this means of securing the frame of the wind-shield to 70 the clamp, the shield may be readily removed and replaced without disturbing the clamp or stationary portion of the supporting structure.

By turning the screw 12 inwardly, the 75 walls 10 and 11 will be drawn toward each other, which will contract the slot and socket and thus firmly clamp the hub therein.

By turning the screw outwardly, the walls 10, 11, will be released and the socket will 80 be free to expand, thereby loosening the hub in the socket, which allows the shield to be adjusted to any desired angle.

By forming the walls of the slot and socket in an unbroken continuation of the 85 post, the walls of the socket will be contracted evenly and caused to clamp the hub at all points around the same, as distinguished from those clamps in which the walls are broken either at the socket or the 90 slot, where the clamping pressure will be uneven and therefore not so effective; the turning strain on the hub in one direction tending to diminish the gripping action of one jaw of the clamp and the turning strain 95 in the other direction tending to diminish the gripping action of the other jaw.

It will be understood that the normal condition of the socket and slot will admit of a free movement of the hub in the socket, 100 so that only a slight movement of the screw is necessary to firmly clamp or release the hub.

It is evident that slight changes might be resorted to in the form, construction and arrangement of the several parts without departing from the spirit and scope of my invention; hence I do not wish to limit myself strictly to the structure herein set forth, but

What I claim is:—

1. In a wind-shield, a post having a cylindrical socket and a longitudinal slot leading from one side of the socket into the post, the walls of the socket and slot forming an unbroken continuation of the post, a hub rotatable in said socket, and means interposed between the socket and the end of the slot for uniformly contracting said socket and slot for clamping the hub against movement.
2. In a wind-shield, a post having a cylindrical socket and a longitudinal slot leading from one side of the socket into the post, the walls of the socket and slot forming an unbroken continuation of the post, a hub rotatable in said socket, a frame carried by said hub, means for removably securing said frame directly to the hub, and means interposed between the socket and the end of the slot for uniformly contracting the

socket and slot for clamping the hub against movement.

3. In a wind-shield, a post provided with a head having therein a cylindrical socket and a slot leading therefrom into the post, the walls of the socket and slot forming an unbroken continuation of the post, a hub rotatable in said socket, a frame having ears, means for removably securing said ears to the hub, and means for contracting said slot and socket for clamping the hub against movement.

In testimony, that I claim the foregoing as my invention, I have signed my name in presence of two witnesses, this 6th day of February 1915.

WILLIAM H. DOUGLAS.
